UNITED STATES PATENT OFFICE.

JOHN KEIM, OF NEW YORK, N. Y., ASSIGNOR TO JOHN S. LEVIS, OF BROOKLYN, NEW YORK.

MEANS FOR PROPELLING BOATS.

SPECIFICATION forming part of Letters Patent No. 591,534, dated October 12, 1897.

Application filed May 6, 1895. Serial No. 548,364. (No model.)

To all whom it may concern:

Be it known that I, JOHN KEIM, of New York, in the county and State of New York, have invented a certain new and useful Improvement in Means for Propelling Boats, of which the following is a specification.

My invention relates to that class of mechanical movements which serve to transform a vibratory or to-and-fro movement into one of continuous rotation about an axis and its adaptation as a means for the propulsion of a boat. The vibratory or to-and-fro movement may be that of one or more levers operated by a person in a manner resembling the operation of the oars of a boat, while the continuous rotation may be that of the propeller-shaft through the revolution of which the boat is driven forward or backward.

I will describe a mechanical movement combined with the propelling apparatus of a boat in which are embodied the features of my improvement, and then point out the novel features in the claims.

In the accompanying drawings, Figure 1 is a plan view of the stern portion of a boat, showing a mechanical movement located therein embodying my improvement and which may be applied to the propulsion of the boat. Fig. 2 is a longitudinal section of Fig. 1 on line 2 2 of that figure. Fig. 3 is a plan view of a modified form of the improvement as adapted to be driven by two persons. Fig. 4 is a cross-section on the line 4 4 of Fig. 3.

Similar letters of reference designate corresponding parts in all the figures.

A is the driven shaft, to which a continuous rotary movement is imparted by means presently to be described. It is journaled in bearings in the present instance supported on a framework B, which is secured within the boat.

For transmitting motion to the propeller-shaft C, I provide the driven shaft A with a bevel-gear c, meshing with a second bevel-gear c', affixed to the propeller-shaft. A sprocket chain and wheels may, however, be used for transmitting motion.

The upper extremity of the driven shaft A carries a crank. In the present instance this

crank is formed by a pin D, carried by a fly-wheel D', the latter being secured to the shaft A to insure steadiness of motion.

E is a three-armed lever, of which three arms I may for the sake of clearness and to avoid repetition designate e as the "fulcrum-arm" 55 and the two remaining arms e' and e² as "power-arms." The three-armed lever E is fulcrumed to the pin D, the fulcrum-point on the lever being situated on the power-arm e², intermediate of its ends. 60

F is a swinging rod pivoted at the point f to the frame B or a stationary part of the boat. At its opposite end the swinging rod F is pivoted to the fulcrum-arm e.

G G' are oar-like levers mounted to swing 65 about pivot-points g and g', respectively, on the gunwales of the boat. The inner ends of these levers may be moved backward and forward similar to oars of a boat. It is evident that a corresponding movement will be 70 given to the outer ends of these oar-like levers. A link H transmits motion from the outer end of the lever G to the power-arm e', while a link H' connects the outer end of the lever G' with the power-arm e² for transmitting motion from the one to the other. 75

I have represented in dotted lines the paths traced by the pivotal points of the various levers and rods during the operation of the mechanism, showing on these paths a series 80 of points designated by numbers to represent the simultaneous positions of the pivotal points at several phases of their movements.

While the outer ends of the levers G and G' vibrate to and fro in the arcs of circles, 85 the paths traversed by the points of attachment of the power-arms e' and e² with the links H and H' will form figures representing ellipses. The two ellipses will be of different forms—that is, the relation between the major and minor axis in each will be different from that in the other and they will be differently positioned.

The person operating the mechanism may sit facing the bow of the boat, in which case 90 I will provide means whereby the boat may be steered by the feet.

I is a foot-rest pivoted to the bottom boards

of the boat at i and adapted to be swung upon its pivot-point by the feet of the operator. A toe-block I' may be supplied.

At each side of the foot-rest I there is an upright rod i' , from the upper end of which there extends a cord i^2 , fastened at one end of the rudder-yoke I^2 . By moving the foot-rest about its pivot-point i the rudder will be swung upon its pivots to steer the boat.

10 Instead of arranging the oar-like levers so that they may be operated by the same person they may be so fitted to the boat as to be operated by two persons, as represented in Figs. 3 and 4. In these figures the various 15 parts may be the same as before, except that the links K and K' are longer than the corresponding links in the construction illustrated in Figs. 1 and 2. The oar-like levers L L' are also shown in these figures as being 20 pivoted to outriggers l l' , while the links L L' are secured to the oar-like levers inboard of the outriggers.

Having described my invention, what I consider as new, and desire to secure by Letters Patent, is—

25 1. A device for propelling a boat the same consisting of a propeller-shaft, a vertical shaft, means for transmitting motion from said vertical shaft to the propeller-shaft, a fly-wheel 30 on said vertical shaft, a three-armed lever mounted on a crank-pin on said fly-wheel, an arm pivotally secured at one end to the boat, the other end of said arm being connected to one arm of the three-armed lever, and means 35 secured to the other two arms of the three-armed lever for transmitting motion thereto, substantially as specified.

2. A device for propelling a boat comprising in combination a rotary shaft, a three-40 armed lever having a pivotal connection with a crank-pin attached to a fly-wheel on said shaft, a vibratory or fulcrum arm pivoted at one end to the boat and at the opposite end to said three-armed lever, oar-like levers fulcrumed to the boat, links connecting said levers with the said three-armed lever, and means for transmitting motion from said rotary shaft to the propeller-shaft substantially as specified.

45 3. A device for propelling a boat having in combination a propeller-shaft, a vertical ro-

55 tary shaft imparting motion thereto, a three-armed lever having a pivotal connection with a crank-pin attached to a fly-wheel on the vertical shaft, a vibratory or fulcrumed arm pivoted at one end to the boat and at the opposite end to said three-armed lever, oar-like levers fulcrumed to the boat, and links connecting said levers with the said three-armed lever, substantially as specified. 60

4. A device for propelling a boat having in combination a propeller-shaft, a second shaft imparting motion to the first shaft, a three-armed lever having a pivotal connection with a crank-pin attached to a fly-wheel on the 65 second shaft, a movable fulcrum for said three-armed lever, and means operated by the rower for vibrating said three-armed lever on its fulcrum, substantially as specified.

5. A device for propelling a boat having in combination a propeller-shaft, a second shaft 70 imparting motion to the first shaft, a three-armed lever consisting of a fulcrumed arm and two power-arms, said three-armed lever having a pivotal connection with a crank-pin 75 attached to a fly-wheel on the second shaft said connection being situated on a power-arm, a movable fulcrum for the fulcrum-arm, and means connected with the power-arms for vibrating said three-armed lever on its 80 fulcrum, substantially as specified.

6. A device for propelling a boat having in combination a propeller-shaft, a second shaft imparting motion to the first shaft, a three-armed lever consisting of a fulcrumed arm 85 and two power-arms said three-armed lever having a pivotal connection with a crank-pin attached to a fly-wheel on a second shaft said connection being situated on a power-arm, a vibratory or fulcrum arm pivoted to 90 the boat and to the fulcrum-arm, oar-like levers fulcrumed to the boat, and links connecting said levers with the power-arms, substantially as specified.

In testimony whereof I have signed my 95 name to this specification in the presence of two subscribing witnesses.

JOHN KEIM.
